US0D1061752S

(12) **United States Design Patent** (10) **Patent No.:** **US D1,061,752 S**
(45) **Date of Patent:** **** Feb. 11, 2025**

(54) **BARBELL**

(71) Applicant: **Coulter Ventures, LLC.**, Columbus, OH (US)

(72) Inventors: **Martin Pritchett**, Columbus, OH (US); **William Henniger**, Columbus, OH (US); **Ahmik Jones**, Upper Arlington, OH (US)

(73) Assignee: **Coulter Ventures, LLC.**, Columbus, OH (US)

(**) Term: **15 Years**

(21) Appl. No.: **29/829,478**

(22) Filed: **Mar. 4, 2022**

(51) LOC (15) Cl. **21-02**

(52) U.S. Cl.

USPC **D21/681**; D21/679; D21/682

(58) **Field of Classification Search**

USPC D21/679, 680, 681, 682, 694; 482/104, 482/106

CPC A63B 21/0724; A63B 21/0728; A63B 21/072

(74) Attorney, Agent, or Firm — Banner & Witcoff, Ltd.

(57) **CLAIM**

The ornamental design for a barbell as shown and described.

DESCRIPTION

FIG. 1 is a top, rear, left perspective view of a barbell showing our new design;

FIG. 2 is a bottom, front, right perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines immediately adjacent to the shaded areas define the bounds of the claimed design and form no part thereof. The broken lines depicting the remainder of the article show portions that form no part of the claimed design.

1 Claim, 8 Drawing Sheets
